CAUTION OF TEXTILES & FIBERS,

UNITED STATES PATENT OFFICE.

HOWARD B. BISHOP, OF NEW YORK, N. Y.

CLEANSING FABRICS.

1,016,928.

Specification of Letters Patent. Patented Feb. 13, 1912.

No Drawing.

Application filed December 2, 1909. Serial No. 531,096.

To all whom it may concern:

Be it known that I, HOWARD BERKEY BISHOP, a citizen of the United States, and resident of the borough of Brooklyn, county 5 of Kings, city and State of New York; have invented a certain new and useful Improvement in the Art of Cleansing Fabrics; of which the following is a specification.

My invention relates to an improvement 10 in the art of cleansing fabrics, being particularly adapted to remove from the same rust stains and other stains, and to sour the fabrics so that the bluing will set properly.

15 Hitherto oxalic acid has been used to neutralize the traces of alkali remaining after the clothes have been washed in soap or another detergent so as to enable the bluing to set, and also to remove iron and other 20 stains, and particularly the yellow edges of collars which are largely due to the iron in the blood given off in perspiration. But oxalic acid makes the clothes feel harsh and stiff and weakens their fiber. This is 25 due to the fact that oxalic acid unites with the lime which is usually present in the clothes or in the washing tank (especially if chlorid of lime has been used as a bleach) and forms calcium oxalate in the form of 30 a fine white, and insoluble powder. This substance settles into the fiber of the clothes, and, being insoluble, is rarely removed by the rinsing process. After repeated washings the cloth becomes filled with this powder, feels hard and stiff, the fibers are weakened, and the turned edges break.

My improvement consists substantially in 40 treating such fabrics with fluorin in the form of any of its water soluble compounds which have an acid reaction. For instance, I may use hydrofluoric acid, hydrofluosilicic acid or any of the water soluble salts, such as the acid salts of the alkalies, for instance, sodium acid fluorid, potassium acid fluorid, 45 ammonium acid fluorid, or sodium silico fluorid ammonium silico fluorid or potassium silico fluorid. On account of its cheapness, the sodium salt of hydrofluoric acid is probably the salt best adapted for practical use, although the ammonium salt is more readily soluble. These substances do not form an injurious precipitate and are easily removed by rinsing.

50 In carrying out my improvement in the art of cleansing fabrics, I may employ a

mixture of two or more fluorin compounds of the character described.

In using the substances above referred to, I add about one pound to about every thousand pounds of the laundry water 60 (without soap), this treatment preceding immediately the usual addition of bluing to the laundry water. In order to neutralize the alkali in the laundry water without using for this purpose the expensive 65 fluorin compound, I may add acid, such as acetic acid, by adding the same to the laundry water previously to or simultaneously with the fluorin compound. Such acid may first be mixed with the fluorin compound 70 and the mixture then added to the water. I may also employ my improvement in the art of cleansing fabrics by mixtures such as fluorin compound or compounds with a gum to form a paste. This paste may be 75 applied directly to the stains and this method of employing my invention is of particular value when it is desired to remove very heavy rust stains.

My improvement in the art of cleansing 80 fabrics results in the neutralization of the alkalies and the removal of rust stains and a large number of other stains in which iron is present without injury to the fabrics, which is an entirely unexpected result, 85 since hydrofluoric acid and many other water soluble compounds of fluorin are commonly believed to have a strong destructive action.

I claim:

1. The improvement in the art of cleansing fabrics which consists in bringing fabrics having iron stains thereon into contact with a water soluble compound of fluorin having an acid reaction, substantially as and for the purpose described.

2. The improvement in the art of cleansing fabrics which consists in bringing fabrics having iron stains thereon into contact with a solution of a water soluble compound of fluorin having an acid reaction, substantially as and for the purpose described.

3. The improvement in the art of cleansing fabrics which consists in bringing fabrics having iron stains thereon into contact with a solution of hydrofluoric acid, substantially as and for the purpose described.

4. The improvement in the art of cleansing fabrics which consists in immersing the same in water, neutralizing an alkali in 110

said water by an acid and adding to the water a water soluble compound of fluorin having an acid reaction, substantially as and for the purpose described.

5. The improvement in the art of removing iron stains from fabrics which consists in moistening and treating the portion of the fabric having the stain, with a water soluble compound of fluorin having an acid

reaction, substantially as and for the purpose described.

In testimony whereof I have hereunto set my hand in the presence of two subscribing witnesses.

HOWARD B. BISHOP.

Witnesses:

JOHN A. KEHLENBECK,
GEORGE V. RASMUSSEN.
